ARTICLE**

Augustus J. Miller III, Jenkintown, Pa.

Application March 8, 1954, Serial No. 29,413

Term of patent 7 years

(Cl. D80—9)

To all whom it may concern:

Be it known that I, Augustus J. Miller III, a citizen of the United States of America, residing at Jenkintown, in the county of Montgomery and State of Pennsylvania, have invented a new, original, and ornamental Design for a Display Device for a Belt or Similar Article, of which the following is a specification, reference being had to the accompanying drawing, forming a part hereof.

Fig. 1 is a front elevational view of a display device for a belt showing my new design; and

Fig. 2 is a side view thereof.

The broken lines shown in Fig. 1 are for illustrative purposes only.

I claim:

The ornamental design for a display device for a belt or similar article, as shown and described.
